UNITED STATES PATENT OFFICE.

JOHN E. McCORKLE, OF HARPER, KANSAS.

WHIFFLETREE.

No. 903,805.

Specification of Letters Patent.

Patented Nov. 10, 1908.

Application filed May 21, 1908. Serial No. 434,127.

To all whom it may concern:

Be it known that I, JOHN E. McCORKLE, a citizen of the United States, residing at Harper, in the county of Harper and State 5 of Kansas, have invented certain new and useful Improvements in Whiffletrees, of which the following is a specification, reference being had to the accompanying drawings.

10 My invention relates to improvements in whiffletrees, and its object is to provide one which is simple and inexpensive in construction and at the same time exceedingly strong and durable.

15 With the above and other objects in view, the invention consists of the novel features of construction and the combination and arrangement of parts hereinafter fully described and claimed and illustrated in the 20 accompanying drawings, in which

Figure 1 is a plan view of my improved whiffletree, one end of the same being in section; Fig. 2 is an edge view; and Figs. 3 and 25 4 are transverse sections taken on the planes indicated by the lines 3-3 and 4-4 in Fig. 1.

•In the drawings 1 denotes the body of my improved whiffletree which is in the form of a wooden beam having a straight front edge and a rear edge inclined forwardly from its 30 center towards its ends so that it is thickest at its center. In said rear edge is formed a centrally disposed longitudinally extending groove or seat 2 of semi-circular shape in cross section to receive a metal stiffening 35 5 rod 4 which is of cylindrical form and has screw threaded ends 5 projecting beyond the ends of the body or beam 1 and through openings 6 formed in the long arms of right angular end plates 7.

40 These plates serve to strengthen and reinforce the ends of the beam or body and have their long arms engaged with the ends of said body and their short arms engaged with the front face of the same and formed with 45 screw threaded openings 8. The latter are adapted to receive fastening screws or bolts 9 which are passed through transverse openings 10 formed in the body 1, the heads 11 of said screws being set in the body beneath the

50 rear edge of the same so that the brace rod 4 passes over them and serves to retain them in position. Nuts 12 are arranged upon the projecting threaded ends 5 of the brace rod

and when tightened serve to securely fasten said rod, the angle plates or irons 7 and the 55 fastening screws 8, to produce a whiffletree which is exceedingly strong and durable and at the same time inexpensive of production.

The whiffletree may be used as either a single tree or a double tree upon vehicles, 60 implements or machines of any description and it may be provided with clevis and draft connections of any form and construction.

Having thus described my invention what 65 I claim is:

1. A whiffletree comprising a body, angular end plates each having an arm engaged with one end of the body and an arm engaged with the front face of the same, transverse fastenings passed through the body and into the forward arms of the angular end plates, a strengthening rod arranged longitudinally on the rear edge of the body and serving to retain said fastenings in the 75 body and means for securing the ends of said rods to the outer arms of said angular end plates.

2. A whiffletree comprising a body formed at its ends with transverse openings and in 80 its rear edge with a longitudinal groove or seat, angular end plates, each having an arm engaged with one end of the body and formed with an opening and another arm engaged with the front edge of the bottom 85 and formed with a screw threaded opening to register with one of the transverse openings in the body, screws passed through said transverse openings in the body and engaged with the threaded openings in said end 90 plates, the heads of said screws being disposed beneath the bottoms of the grooves in the rear face of the body, a strengthening rod arranged in said longitudinal groove in the rear face of the body and extending over 95 the heads of said screws, the projecting ends of the rod being adapted to project through the openings in said angular plates and being screw threaded, and nuts upon the projecting threaded ends of the rod. 100

In testimony whereof I hereunto affix my signature in the presence of two witnesses.

JOHN E. McCORKLE.

Witnesses:

JOHN A. BARNES,
JOHN BAUMSTAUK.
